DESIGN FOR A SYRINGE

Arthur E. Smith, Los Angeles, Calif.

Application March 6, 1942, Serial No. 106,102

Term of patent 14 years

To all whom it may concern:

Be it known that I, Arthur E. Smith, a citizen of the United States, residing at Los Angeles, in the county of Los Angeles and State of California, have invented a new, original, and ornamental Design for a Syringe, of which the following is a specification, reference being had to the accompanying drawing, forming a part thereof.

In the accompanying drawing,

Fig. 1 is a side elevational of a syringe showing my new design;

Fig. 2 is a section taken on line 2—2, Fig. 1;
Fig. 3 is a front end view of the syringe; and
Fig. 4 is a rear end view of the syringe.

I claim:

The ornamental design for a syringe, as shown.

ARTHUR E. SMITH.
